US0D1104078S

(12) **United States Design Patent** (10) **Patent No.:** **US D1,104,078 S**
(45) **Date of Patent:** **** Dec. 2, 2025**

(54) **TIP FOR A GROUND ENGAGING MACHINE IMPLEMENT**

(71) Applicant: **Caterpillar Inc.**, Peoria, IL (US)

(72) Inventors: **Corey M. Wells**, East Peoria, IL (US);
Thomas M. Congdon, Dunlap, IL (US); **Mitchell Spencer**, Washington, IL (US)

(73) Assignee: **Caterpillar Inc.**, Peoria, IL (US)

(**) Term: **15 Years**

(21) Appl. No.: **29/942,404**

(22) Filed: **May 15, 2024**

(51) LOC (15) Cl. **15-03**

(52) U.S. Cl.

USPC **D15/29; D15/28**

(58) **Field of Classification Search**

USPC D15/10, 11, 12, 13, 17, 21-26, 28, 29, D15/32, 139; D8/6, 8

(57) **CLAIM**

The ornamental design for a tip for a ground engaging machine implement as shown and described.

DESCRIPTION

FIG. 1 is a perspective view of a tip for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines depict portions of the tip for a ground engaging machine implement which form no part of the claimed design.

1 Claim, 5 Drawing Sheets
